UNITED STATES PATENT OFFICE.

ROBERT W. WADE, OF BALTIMORE, MARYLAND.

SASH-CORD FASTENER.

1,172,850.

Specification of Letters Patent. Patented Feb. 22, 1916.

Application filed April 3, 1914. Serial No. 829,394.

To all whom it may concern:

Be it known that I, ROBERT W. WADE, a citizen of the United States, residing at Baltimore, State of Maryland, have invented 5 certain new and useful Improvements in Sash-Cord Fasteners; and I do hereby declare the following to be a full, clear, and exact description of the invention, such as will enable others skilled in the art to which 10 it appertains to make and use the same.

This invention relates to improvements in fastening devices and more particularly to a fastener employed for attaching the weight cord to a window sash, and the primary 15 object of the invention is the provision of a fastener constructed with a single strand or length of wire bent to form a cord engaging portion and sash engaging portion for detachably attaching the weight 20 cord to a window sash.

With the foregoing and other objects in view, this invention consists in such novel features of construction, combination and arrangement of parts as will be hereinafter 25 more fully described, illustrated in the accompanying drawings and claimed.

In describing the invention in detail, reference will be had to the accompanying drawings, wherein like characters designate 30 like or corresponding parts throughout the several views, and in which,

Figure 1 is a view of a window sash showing parts of the same broken away to expose the improved weight cord fastener attached 35 thereto, Fig. 2 is an enlarged end view of the sash showing the cord fastener applied thereto, and, Fig. 3 is a detail perspective view of the improved fastener.

Referring more particularly to the drawings, 1 designates a window sash of any 40 ordinary construction, which has the side strips 2 and 3, for engagement with the frame of the window, and which end pieces are slidably mounted in the window frame 45 (not shown) the vertical sliding movement of the same being regulated by weights (not shown) carried by the window frame (not shown). In the construction of window frames of this nature, the weights are suspended 50 within the window frame or casing, and passing over pulleys (not shown), are connected to the sides of the window sash, and Fig. 1 of the drawing shows the window sash weight cord 4 or flexible member extending 55 downwardly along the sides 2 and 3 of the window sash being positioned in the

vertically extending slots 5, which slots are formed in the outward edges of the sides 2 and 3 of the window sash 1. The slots 5 terminate inwardly in an enlarged recess 6, 60 which recess is provided for the reception of a knot 7, which is formed on the terminal end of the weight cord 4, and the weight cord 4 is held in engagement with the window sash 1, and properly positioned in the slot 5 by 65 the engagement between the knot 7 and the angled connected end 8 of the fastening member 9.

The fastening member 9 is constructed of a single strand or length of wire, having its 70 terminal ends 10 and 11 sharpened for insertion into the sides 2 or 3 of the window sash 1, the wire is bent inwardly substantially at right-angles to the terminal ends 10 and 11, as is shown at 12 and is again bent up at 13, 75 forming an elongated cord gripping portion 14, which extends substantially at right-angles to the straight terminal ends 10 and 11, and also to the sections of the wire positioned between the corners 12 and 13, lying 80 in a plane with the latter sections, and forming a substantially U-shaped cord engaging portion. The terminal end or the connected portion of the U-shaped cord engaging section is bent downwardly a short distance in- 85 wardly from the terminal end thereof, for transverse positioning in the slot 5, as is clearly shown in Figs. 1 and 2 of the drawings.

In the application of the improved cord 90 fastener, the ends 10 and 11 of the cord fastener 9 are driven into the ends 2 or 3 of the sash, marginally of the recesses 6, and the U-shaped cord engaging portions extend longitudinally within the groove 5, having 95 its angled terminal end extending transversely into the groove. The weight cord 4 is positioned so the knot 7 formed on the terminal end thereof, may be inserted into the recess 6, rearwardly of the sections of 100 the fastening device between the angles 12 and 13, and it is then drawn upwardly, so that the knot 7 will pass between the substantially parallel straight arms 14 being securely held therein for the engagement of 105 the knot with the wall of the recess 6, while the arms 14 prevent the knot from being forced out of the recess 6. The angle connected end of the U-shaped cord engaging portion forms a guide for the weight cord 110 and further facilitates in preventing the removal of the cord 4 from the slot 5.

Having thus fully described the invention, what is claimed is:—

A sash cord fastener comprising a single length of wire, bent to assume substantially two parallel arms of equal length, the ends 5 of said arms being bent outwardly in alignment with and inwardly transversely to said arms, the inwardly extended portions being sharpened forming sash engaging ends, and

having the upper connected end of said 10 parallel arms bent inwardly at right angle thereto.

In testimony whereof I affix my signature in presence of two witnesses.

ROBERT W. WADE.

Witnesses:

FRANCES T. BANNON,
CAMILLA D. NICHOLSON.
